UNITED STATES PATENT OFFICE.

GEORGE CROWTHER, OF CINCINNATI, OHIO, ASSIGNOR OF ONE-HALF TO
THEODORE NIEMAN, OF SAME PLACE.

BEDSTEAD.

SPECIFICATION forming part of Letters Patent No. 316,335, dated April 21, 1885.

Application filed March 31, 1884. (No model.)

To all whom it may concern:

Be it known that I, GEORGE CROWTHER, of Cincinnati, Hamilton county, Ohio, have invented a new and useful Improvement in 5 Slat-Fasteners for Bedsteads, of which the following is a specification.

The invention relates to an improvement in those bedsteads whose "bottoms" or supports for the bedding comprise series of 10 wooden slats; and the invention consists in a substitute for the customary wooden "guards" or space-blocks—such as are usually glued in the side-rail rabbets—to hold the slats their proper distance apart. The improvement 15 comprises a tongue or guard, preferably composed of sheet metal, so stamped, by means of a suitable die, as to possess two spurs, which enable it, by a few blows given by a hammer or mallet, to be securely fastened to the rail. 20 A saw cut or kerf in the slat end, by engaging over such tongue, causes the slat to be retained securely and accurately in place.

In comparison with the ordinary wooden space-blocks, the device is stronger, more durable, neater, cheaper, and more vermin-proof. 25

In the accompanying drawings, Figure 1 represents, by perspective view, portions of a side rail and slat of a bedstead embodying my invention. Fig. 2 is a profile of my guard 30 or tongue in its preferred form. Fig. 3 represents, by top view, a portion of such a bedstead with its tongues and slats in position. Figs. 4 and 5 show modifications of my slat-guard.

A may represent customary bed-post; B, side rail; b, side rail rabbet; C, tongue or guard having a body of rectangular form; c c', spurs thereof.

D represents wooden slats; d, saw cuts or 40 kerfs in their ends of dimensions just sufficient to receive and snugly inclose the appropriate tongues, of which there are two to each slat.

A set of tongues being, by means of a hammer or mallet, driven at equal consecutive 45 distances into the side rails, as represented, become at once sufficiently attached to forthwith apply the slats as shown in Fig. 3.

Various metals, either cast or wrought, may 50 be employed for the tongues, but the material preferred and used by me is what is known as "No. 14 spring sheet-brass."

Over the common wooden space-blocks my

metallic guards possess several notable advantages—for example, they are more permanent, their shape and their mode of attachment being such as to dispense with the use either of nails or of the more customary and general fastening by gluing. The usual fastening, glue, is liable to give way with a sudden strain or blow, or by the softening effect of continuous wet weather, or of scalding water employed to destroy vermin. The fastening, being partly metallic, is far less favorable to vermin, to which metal surfaces are notoriously obnoxious. When the rabbet, as is usually the case, is formed by nailing or gluing the slat-supporting cleat to the rail proper, my metallic guards constitute a valuable additional bond between these two members.

Than the common blocking, the present device possesses a neater and more finished appearance, can be applied in a small fraction of the time and at one-half the cost, and is immediately available, it not being necessary to await the drying of glue, none being employed.

The tongue or guard may be varied in non-essential particulars—for example, it may have a cutting or piercing top edge, (see Fig. 80 4 or Fig. 5,) and the slat be applied by pressure or percussion, in which case no kerf in the slat is necessary.

I claim as new and of my invention—

1. In combination with a bedstead frame 85 and slats, the slat-fasteners consisting of vertical plates or metallic tongues C, having spurs c and c', the upper edges of the plates or tongues being formed to receive the ends of the slats in line therewith and transverse 90 of the bedstead-frame.

2. The combination, with a bedstead-frame, of the tongues C, having spurs c c', and arranged transverse of the rabbets, and the slats D, having longitudinal kerfs d in their ends 95 occupied by the upper edges of the tongues.

3. As a new article of manufacture, a slat-fastener for bedsteads, consisting of a tongue, C, having a body of rectangular form, provided with spurs c and c', and an upper edge 100 adapted to enter slat ends in line therewith.

In testimony of which invention I hereunto set my hand.

Attest: GEORGE CROWTHER.

GEO. H. KNIGHT,
S. S. CARPENTER.
